CLAIM

The ornamental design for a wind turbine nacelle, as shown and described.

DESCRIPTION

1. Wind turbine nacelle

2. Wind turbine nacelle

Design no. 1 is a wind turbine nacelle; Design no. 2 is a wind turbine nacelle.

Figure 1.1 is a front and right side perspective view of a first embodiment of a wind turbine nacelle showing the new design;

Figure 1.2 is a front elevation view thereof;

Figure 1.3 is a rear elevation view thereof;

Figure 1.4 is a top plan view thereof;

Figure 1.5 is a bottom plan view thereof;

Figure 1.6 is a left side elevation view thereof;

Figure 1.7 is a right side elevation view thereof;

Figure 1.8 is a rear and right side perspective view thereof;

Figure 2.1 is a front and right side perspective view of a second embodiment of a wind turbine nacelle showing the new design;

Figure 2.2 is a front elevation view thereof;

Figure 2.3 is a rear elevation view thereof;

Figure 2.4 is a top plan view thereof;

Figure 2.5 is a bottom plan view thereof;

Figure 2.6 is a left side elevation view thereof;

Figure 2.7 is a right side elevation view thereof; and

Figure 2.8 is a rear and right side perspective view thereof.
